UNITED STATES PATENT OFFICE.

ZIGMUNT SLAWINSKI, OF PLAINFIELD, NEW JERSEY.

SKATE.

1,342,773.

Specification of Letters Patent. Patented June 8, 1920.

Application filed October 22, 1919. Serial No. 322,497.

To all whom it may concern:

Be it known that I, ZIGMUNT SLAWINSKI, a citizen of Poland, residing at Plainfield, in the county of Middlesex and State of New Jersey, have invented certain new and useful Improvements in Skates, of which the following is a specification.

This invention relates to roller and ice skates, and the like, and has for its object the provision of novel clamping means for such skates, of novel means for varying the wheel-base of roller skates, and of novel structure of the wheels and bearings thereof, and a proper tool for use therewith.

15 The above and other objects will become apparent in the description below, in which characters of reference refer to like-named parts in the drawings.

Referring briefly to the drawings, Figure 20 1 is a plan view of the underside of a roller skate built according to my invention, the wheels thereof being removed.

Fig. 2 is an enlarged view of the clamp operating mechanism of my device.

25 Fig. 3 is a side elevational view of the rear portion of my roller skate.

Fig. 4 is a side elevational view of my adjustable means for varying the wheel base of a skate.

30 Fig. 5 is a side elevational view of a wheel, the interior being partly exposed, built according to my invention.

Fig. 6 is a side elevational view of the ball frame of the above view.

35 Fig. 7 is a front elevational view of the same.

Fig. 8 is a plan view of my novel tool.

Referring now in detail to the drawings, 1 represents the rear base member of a roller 40 skate, and 2 the forward member thereof.

Truck frames, upon which are supported the front and rear wheels, are indicated by 6 and 7, respectively. Members 10 and 10^a are rigid to the undersides of their respective 45 base members, and are provided with threaded holes for the reception of the cylindrical screw 3, which is provided as shown with lock nuts 8, 8^a, and 9.

The customary clamps 4 are guided by 50 pins 5 projecting through said clamps, and are further constrained to longitudinal motion by the overlapping bands 4^a on said base 2. A curved link 43 is rigidly attached to one of said clamps 4, and pivotally connected at its other end to a link 12, which in turn is pivotally connected to another link

15. Said link 15 is then pivotally attached to the end of a lever 42 which is pivotally mounted at 44 to the other of said clamps 4. An upwardly projecting handle or knob 45 60 is provided at the free end of said lever, and a spring 16 is attached to said lever as shown the other end thereof being attached to the base 2. A spring 13 is attached at one end to the common point between the left-hand 65 clamp 4 and the link 43, and at the other end to the support 7; this spring is broken in Fig. 2 so as to allow the illustration of the clamp operating mechanism when the clamps are both in open and closed positions. 70

The operation of this device is simple, and is readily illustrated in Fig. 2. By motion of the lever 42 to the right, the clamps are separated, and on release of the lever 42 the springs 13 and 16 cause the clamps to 75 close against the shoe of the wearer of the skate.

To lengthen or shorten the wheel base of the skate, it is necessary simply to grip one of the members 1 or 2 in one hand, and rotate the other until the desired length is attained; or both members 1 and 2 may be stationary, and the screw 3 may be rotated. For this latter operation my tool, later to be described, is particularly adapted. 85

My wheel construction is as follows: The rim of the wheel is indicated at 25; inside of this rim is a ball frame 28 having circular cup recesses therein for the retention of balls 29 of hard steel. These balls are 90 free to rotate therein, and the frame 28 is of a width about two-thirds of the diameter of said balls, so that when they are in their recesses, about one-sixth each, ball, projects both above and below said frame, as clearly 95 illustrated in Fig. 5.

The upper portion of said balls thus contacts with the inner periphery of the rim 25, and the lower portion with the inner surface of the enlargement 26 of the hub 27. 100 When the wheel is in place on the skate, a flat rim or washer 21 fits over the exposed balls and frame 28. A nut 46 is screwed upon the axle of the wheels to retain them thereon. 105

Fig. 3 illustrates my means for fastening the skate to the rear of the shoe. A brace or support 40 is mounted rigidly to the underside of the base 1, its ends curving upward and having pivoted thereto a pair of 110 metal reinforcing frames 22, at 41. A band or cover of leather or the like 20 is rigid

about said members 22, and a strap 24 having a fastening buckle 23 is secured to said band, for the purpose of binding the same about the shoe.

5 My tool is indicated in Fig. 8, wherein 35 represents the handle, and 36 the metal frame, the forward end 47 of which is of a thickness slightly less than the width of the opening 3^a on the end of the screw 3, 10 so that the former may be used to turn the latter. A recess 37 therein is of a semi-periphery slightly larger than that of the nuts 8, 8^a, and 9, so that the former may be 15 adjusted about any of the latter to turn the same. Similarly the recess 38 is adjustable about the nuts 46.

Having thus described my invention, what I claim and desire to secure by Letters Patent is as follows:

20 1. In a device of the class described, front and rear members having means to support wheels thereon, means for varying the wheel base of the device comprising a screw having pivotal support in said members, lock

nuts therefor, and rocking-lever actuated 25 clamping means therefor.

2. In a device of the class described, front and rear members, means for adjusting the wheel base of the device, and clamping means therefor comprising a pair of clamps 30 slidably mounted on the underside of said forward member, a lever pivotally secured to one of said clamps, links connecting said lever to the other of said clamps, and spring means to retract said clamps after they have 35 been separated.

3. In a device of the class described, front and rear members, clamps on the front member slidable in pins thereon, a lever pivoted to one of said clamps, a handle on one end 40 of said lever, a spring connecting said lever with said front member, a plurality of links connecting said lever with said other clamp, a second spring connecting said last-named clamp with said front member, and guides 45 for said clamps.

In testimony whereof I affix my signature.
ZIGMUNT SLAWINSKI.
